UNITED STATES PATENT OFFICE.

FRANK SWEET, OF BUFFALO, NEW YORK, ASSIGNOR TO PHILIP R. SWEET, OF BUFFALO,
NEW YORK.

METAL BOAT.

1,358,479.

Specification of Letters Patent.

Patented Nov. 9, 1920.

Application filed July 25, 1919. Serial No. 313,226.

To all whom it may concern:

Be it known that I, FRANK SWEET, a citizen of the United States, residing at Buffalo, in the county of Erie and State of New 5 York, have invented a new and useful Improvement in Metal Boats, of which the following is a specification.

This invention relates to improvements in boats, launches, tugs or the like, which are 10 made of metal.

The objects of this invention are to produce a boat of this kind constructed of corrugated metal secured to metal ribs in such a manner as to produce a strong and durable construction; also to so construct the boat that the lower edge portions thereof will be more durable and will not cause the boat to leak if these edge portions are chafed through; also to provide the boat with a bow 15 plate or nose piece of improved construction; also to provide the boat with removal metal seats; also to improve the construction of devices of this kind in other respects hereinafter specified.

25 In the accompanying drawings:—

Figure 1 is a side elevation of a metal boat embodying the invention.

Fig. 2 is a top plan view thereof.

Fig. 3 is a fragmentary, longitudinal, sectional elevation thereof on an enlarged scale 30 on line 3—3, Fig. 2.

Fig. 4 is a fragmentary, transverse, sectional elevation thereof on line 4—4, Fig. 1.

Fig. 5 is a rear elevation thereof.

35 Fig. 6 is a transverse sectional elevation thereof on line 6—6, Fig. 2.

Fig. 7 is a fragmentary, longitudinal, sectional elevation on a still larger scale on line 7—7, Fig. 5.

40 Fig. 8 is a fragmentary, sectional, plan view thereof on line 8—8, Fig. 1.

The boat shown in the accompanying drawings is of the flat bottom type but it will be understood that the invention is not 45 limited to this type of boat since a round-bottomed boat may embody the features of the invention.

The boat includes a bottom A, sides B and a stern C, all of which are made of corrugated sheet metal, the corrugations at the bottom and sides of the boat extending lengthwise of the boat so as to afford very little resistance to the movement of the boat through the water and so as to strengthen

the boat lengthwise. The corrugated metal 55 is secured to the framework of the boat, which in the construction shown is made of angle irons but which may be made of channel beams or members of other sectional shape and which includes two lower angles 60 or longitudinal frame members D, and upper angles or longitudinal frame members E, the upper and lower longitudinal frame members being bent to conform to the shape of the boat and preferably meet at a point 65 at the bow of the boat. The lower longitudinal members D are connected at intervals by means of transverse members F and the upper and lower longitudinal members are connected by means of ribs or upright frame 70 members G. The corrugated metal is riveted or otherwise suitably secured to the longitudinal, transverse and upright frame members, the rivets being arranged in the parts of the corrugations touching the frame 75 members.

The lower edges of the boat are preferably formed by bending the bottom plate A upwardly to overlap the side plates, and the edges of both plates are secured to the upwardly extending flanges of the angle irons D, the lower edges of the side plates extending beneath the bottom in the form of hooks. The bottom A is also preferably secured to the lower flanges of the lower longitudinal members, the upwardly extending portions of the bottom plate being bulged downwardly and outwardly from the angle irons D and overlying the hooked portions of the sides B, thereby forming the rounded 85 edges H. The connections between the bottom and side plates and the angles D are preferably made by means of rivets h and the bottom and side plates are preferably also welded to the angles D throughout their 90 length in such a manner as to form a watertight joint between the bottom and side plates and the lower longitudinal members. The rounded edges H formed at the meeting of the sides and bottom plates form skids or 100 slides of double thickness of metal for the boat when the same is out of water. By welding the side and bottom plates to the lower longitudinal members D, a water-tight joint is formed between the angles and the 105 plates so that the wearing out or chafing through of the portions H of the plates does not cause leaking of the boat and the pro-

vision of this joint together with the skids H of double thickness greatly prolongs the life of the structure.

The nose or bow of the boat is preferably provided with a plate I bent substantially into V-shape and covering the front ends of the side plates. The edges of the plate I are preferably bent so as to fit within the corrugations of the side plates of the boat and are welded to the side plates, thus forming a water-tight connection and also reinforcing the bow of the boat.

The stern C of the boat is preferably made by means of a piece of metal, the corrugations of which are arranged vertically. The joints or seams between the bottom plate, stern plate and side plates are preferably welded so as to form a rigid and secure structure and to form water-tight seams. At the bow and the stern the boat is partly decked over by means of corrugated pieces K and K' which are secured to deck beams k k' respectively, the deck beams connecting the upper longitudinal frame members E and reinforcing the same.

The seats may be arranged in the boat in any desired manner. In the construction shown the seats are made removable and each seat comprises a metal plate L which, if desired, may also be of corrugated metal and which is secured at one side to a beam l which is secured at its opposite ends to upright frame members G, preferably by means of bolts which permit the beam l and plate L connected thereto to be removed from the boat. The plates L are supported in their operative positions by means of cleats or the like l', which in the construction shown are in the shape of angle beams secured to the corrugated side plates B of the boat and on which the ends of the seats rest. The beams l of the seats also act as a reinforcement for the upright members G of the frame of the boat.

The structure described has the advantage that the corrugations of the side and bottom plates reinforce the frame so that only four longitudinal frame members are needed for a boat of considerable size. By using corrugated metal, the plates may be thinner, since the corrugations increase the strength thereof and resist denting or otherwise deforming the plates. The manner of joining the edges and side plates of the boat insures a water-tight construction, requiring no calking and prevents leaks even when the metal of the portions H is worn through.

By making the seats removable, the interior arrangement of the boat may be readily changed to suit the user.

I claim as my invention:

1. In a metal boat, the combination of a frame including upper and lower longitudinal members, and side plates and bottom plates extending throughout the length of the boat and made of corrugated metal arranged with the corrugations extending lengthwise of the boat, the lower edges of the side plates and the outer edges of the bottom plate being bent outwardly and overlapping and forming skids of a double thickness of metal and being welded to said lower longitudinal members at opposite sides of said skids whereby the wearing out of said skids will not cause leaking.

2. In a metal boat, the combination of a frame including lower longitudinal members consisting of angle irons, and side plates and bottom plates extending substantially throughout the length of the boat and having corrugations extending lengthwise of the boat, the lower edges of the side plates extending beneath the bottom in the form of hooks, the side edges of said bottom plate projecting downwardly, outwardly and upwardly from said lower longitudinal members and overlapping the hooked portions of said side plates, said bottom plate being welded to the horizontal side of the angle iron and said side plates being welded to the vertical side of said angle iron, thereby forming skids between said welded connections.

3. In a metal boat, the combination of a frame, side plates having corrugations extending lengthwise of the boat and meeting at the bow of the boat, a bow plate bent into substantially V-shape and connecting the ends of said side plates at the bow, the edges of said bow plate being bent to conform to said corrugations of the side plates and being secured to said side plates to form a water-tight connection therewith, and a stern plate to which the rear ends of said side plates are connected, said bow and stern plates being fitted to the corrugated side plates and being welded thereto to form water-tight connections.

Witness my hand this 19 day of July, 1919.

FRANK SWEET.
